ALBUM

John Pienzak, Deming, N. Mex.

Application June 19, 1936, Serial No. 86,179

4 Claims. (Cl. 129—1)

This invention relates to albums and the object of the invention is to provide an album particularly adapted for the mounting and displaying of stamps, coins or the like.

5 More particularly an object of the present invention is to provide in an album an improved loose leaf binder clamp and assembly.

The invention together with its objects and advantages will be best understood from a study 10 of the following description taken in connection with the accompanying drawings wherein:

Figure 1 is a plan view of the album in closed position illustrating certain features hereinafter more fully referred to.

15 Figure 2 is a detail sectional view taken substantially on the line 2—2 of Figure 1.

Figure 3 is a detail sectional view taken substantially on the line 3—3 of Figure 4.

20 Figure 4 is a detail plan view of the binder clamp with the back of the album in open position, and with the protector plate removed.

Figure 5 is a plan view of a portion of one of the backs showing the latch means for the album.

25 Figure 6 is a detail view taken substantially on the line 6—6 of Figure 5.

Figure 7 is a fragmentary plan view of the album with one of the backs folded to open position.

Figure 8 is a detail sectional view taken substantially on the line 8—8 of Figure 1.

Figure 9 is a plan view of a key.

Figure 10 is a plan view of a portion of one of the sheets of the album.

Figure 11 is a perspective view of a cover plate 35 for the binder clamps.

Figure 12 is a fragmentary plan view of a portion of the binder clamp assembly with the sliding manipulating handle of the assembly in outward or extended position.

40 Figure 13 is a side elevational view showing the binder set up for perusal or any analogous purpose.

Figure 14 is a detailed sectional view showing the manner of detachably fastening the adjacents 45 of two edge strips together.

Referring to the drawings by reference numerals it will be seen that the album comprises a pair of cover members 5, 6 which at one edge are hinged to a back 7 as indicated generally at 8.

50 The cover members 5 and 6 may be formed from any suitable material, such as ply wood, cardboard or the like and are preferably provided with a covering 9 of suitable fabric as suggested in Figure 1.

55 The back 7 is in the form of an elongated chan-

nel member which houses the binder clamp hereinafter more fully described.

Hinged to the respective opposite ends of the back 7 are what may be termed edge strips 9 and 10 respectively. The strips 9 and 10 at one end are hinged to the ends of the back 7 as indicated generally at 11.

The member 9 is in the form of a single strip that is of a length substantially slightly less than the width of the album while the strip 10 consists of a pair of sections hingedly connected together as at 12.

The cover member 5 has hinged to its free longitudinal edge as at 13 an edge strip 14 to the inner side of which are suitably secured relatively spaced plates 15 formed with eyes 16 which, when the album is in the closed position project through openings 17 provided in a plate 18 secured to the cover member 6 at the inner side of the latter as shown in Figures 6 and 8.

20 The portion of the plate 18 provided with the openings 17 is disposed opposite an elongated slot 19 provided in the aforementioned cover member 6, and working within the slot 19 is a latch rod 20, operating in suitable guides 21 provided therefor and suitably provided at its opposite ends to engage in the eyes 16 in a manner clearly shown in Figure 5 for releasably securing the album in closed position.

25 For shifting the rod 20 into and out of latching engagement with the eyes 16 there is provided a key operated arm 23 pivoted intermediate its ends as at 24 within a lateral slot 25 provided in the cover member 6 and pivoted at one end to an intermediate portion of the rod 20 as at 26. The member 23 is suitably formed at the pivot 24 thereof and at the end 27 thereof to accommodate a suitably provided key 28 (see Figure 9) which is used for rocking the arm 23 to latch or unlatch the album.

30 Secured to the outer face of the cover member 6 and disposed over the aforementioned slot 19 is a suitable cover plate 30. As shown in Figure 1, plate 30 is provided with a suitable keyhole 31 to accommodate the key 28. In this connection it will also be noted that the plate 30 will be concealed by the fabric covering 9 which of course will be suitably provided with an opening registering with the keyhole 31.

35 To provide for a firm rigid structure when the album is in completely closed position there are provided at the top and bottom edges of the cover members 5 and 6 and at the respective opposite end edges of the edge member 14 lugs 32 preferably formed of metal and secured to the afore-

mentioned parts in a manner clearly shown in Figure 2. Complemental to the lugs 32 are spring clips 33 provided on the longitudinal edges of the edge strips 9 and 10 and in the free end edges 5 of said strips 9 and 10 and with which the lugs 32 engage in a manner clearly shown in Figure 2 when the parts are in fully closed position.

In accordance with the present invention the binder clamp comprises, as best shown in Figures 3, 4, and 8 a pair of oppositely disposed guides 34 disposed transversely within the back 7 and respectively having their respective opposite ends accommodated within side channels 35 provided in the sides of the back 7, and in this connection it will be also noted the guides are accommodated in suitable channels 36 provided in the end wall of the back 7.

Each of these guides 34, which guides are secured in the back in any suitable manner are 20 provided with upper and lower channels 37, 38.

Slidably fitting within the channels 37, 38 of each guide are racks 39 which have projecting outwardly and upwardly from one side thereof arms 40 provided at their upper ends with substantially tubular prongs 41. The prongs 41 are longitudinally slit and are adapted to telescope as shown in Figure 3 for holding the leaves 42 of the album by passing through the openings provided adjacent the marginal edge of the 30 leaves.

For operating the racks 39 there is provided a shaft 42 that extends through suitable openings provided therefor in the guides 34 and the shaft 42 is provided in any suitable manner with pinions 43 that mesh with the racks in the manner clearly shown in Figure 3. Obviously as shaft 42 is rotated the racks will be moved transversely either inwardly or outwardly carrying with them the prongs 41 to which the racks are connected 40 through the medium of the arms 40 in a manner above described. Manifestly the racks in each guide are moved relative to one another either for telescoping the prongs 41 to secure the leaves 42 to the binder clamps or to move the prongs 45 outward relative to one another to separate the prongs to permit of a removal or a replacement of a leaf 42.

To facilitate rotation of the rod 42 to shift the prongs as and for the purposes above mentioned 50 there is slidably associated with one end of the shaft 42 a handle 53 having a squared interior which receives a squared end of the shaft 42. Normally the handle 53 is in the retracted position shown in Figure 4 so as not to interfere with 55 a closing of the binder. However when it is desired to manipulate the shaft 42 to actuate the prongs of the binder clamp handle 53 is slid outwardly to the position shown in Figure 12 and when in this outward position the shaft may be 60 rotated readily for actuating the prongs.

Shaft 42 is journalled in suitable bearings 44 provided therefor within the back 7.

Removably fitted within the back 7 is a cover or protector plate 45 which fits between the sides 65 of the back and is provided with notches 46 in the longitudinal edges thereof to accommodate the arms 40 and not to interfere with the free movement of the prongs to opened or closed position.

As shown in Figure 11 cover plate 45 has down-turned end edges 47, and one of these end edges is provided with a notch 48 as shown and through 70 which the handle member 53 operates. Thus it will not be necessary to disturb the plate 45 to 75 obtain access to the handle member 53.

To protect the apertured edges of the leaves 42 there are provided as shown in Figure 8 plates 49 of suitable material and these plates are suitably apertured to receive the prongs 41.

In the present instance the leaves 42 are provided with suitable pockets 50 into which may be placed stamps, coins, or the like which are collected.

When it is desired to make use of the album, in looking through the album or for other purposes the same when in open position may be set up as in Figure 13 wherein it will be seen that the end strips 9 and 10 may be swung to the position shown in Figure 13 with one section of the end strip 10 forming a post, and the other section of the end strip 10 lapped by the free end of the strip 9 and cooperating with the strip 9 to provide a base upon which the album at the back 7 thereof is supported on a table or the like in a manner convenient for turning the pages 20 of the album in looking through the same.

Having thus described the invention, what is claimed as new is:

1. An album comprising a back member, cover members hinged to the back member at opposite sides of the latter, opposed transverse guides fixedly mounted in said back, a pair of racks mounted in each guide for sliding movement therein, loose-leaf retaining prongs carried by said racks and movable therewith, a shaft extending longitudinally of said back and through openings in said guides, pinions on said shaft meshing with the racks for simultaneously shifting the racks of each pair relative to one another to move said prongs either inwardly relative to one another or outwardly relative to one another, optionally, end strips hingedly connected at one end to the respective opposite ends of said back, said end strips adapted to be disposed between said cover members when the album is closed, and inter-engaging means on said end strips and on said cover members engaging when the album is closed to releasably hold the mentioned parts of the album in fixed position relative to one another. 30

2. In an album of the character described, a back, cover members hinged to the back at opposite sides of the latter, a strip hinged to one of the cover members adjacent the edge thereof opposite to said back, said strip having eyes 50 projecting from a free longitudinal edge thereof, and the other of said cover members having adjacent an edge thereof openings through which said eyes extend when the album is closed, a latch bar slidably mounted on the second mentioned cover member and having ends engageable in the eyes for securing the album in closed position. 55

3. In an album of the character described, a back, cover members hinged to the back at opposite sides of the latter, a strip hinged to one of the cover members adjacent the edge thereof opposite to said back, said strip having eyes projecting from a free longitudinal edge thereof, and the other of said cover members having adjacent an edge thereof openings through which 60 said eyes extend when the album is closed, a latch bar slidably mounted on the second mentioned cover member and having ends engageable in the eyes for securing the album in closed position, an arm pivotally mounted on the second named cover member and having an end pivotally connected with the latch bar for shifting the latter into and out of engagement with said eyes, and said pivoted arm provided with means 65 70 75 75

requiring a key of a predetermined structure to be engaged therewith for rocking the pivoted arm.

4. In an album of the character described, a back, cover members hinged at one edge to the back at opposite sides of the latter, top and bottom end members hinged at one end to the respective opposite ends of said back, said top and bottom members adapted to be disposed between

the cover members when the album is closed, and one of said end members comprising a pair of hinged sections and cooperable with the other of said end members to provide a support for supporting the album when in open position with the back of the album disposed at substantially an acute angle to a flat supporting surface. 5

JOHN PIENZAK.
